CARRIER FOR MILK CARTONS OR THE LIKE

Costis J. Paps, 866 N. Wabash Ave., Chicago, Ill.

Filed Nov. 7, 1960, Ser. No. 62,748

Term of patent 14 years

(Cl. D58—26)

FIG. 1 is a top perspective view of a carrier for milk cartons of the like showing my new design;

FIG. 2 is bottom perspective view thereof; and

FIG. 3 is a end elevational view thereof.

The side not shown a mirror image of the side shown.

I claim:

The ornamental design for a carrier for milk cartons or the like, as shown and described.
